UNITED STATES PATENT OFFICE.

JANET REES AND GLADYS REES, OF DES MOINES, IOWA.

ATTACHMENT FOR HAIR-DRESSERS' CHAIRS.

1,149,541.

Specification of Letters Patent. Patented Aug. 10, 1915.

Application filed March 9, 1914. Serial No. 823,596.

To all whom it may concern:

Be it known that we, JANET REES and GLADYS REES, citizens of the United States, and residents of Des Moines, in the county 5 of Polk and State of Iowa, have invented a certain new and useful Attachment for Hair-Dressers' Chairs, of which the following is a specification.

The object of our invention is to provide 10 an attachment for hair dressers' chairs of simple, durable and inexpensive construction, adapted for holding toilet preparations and the like.

More particularly it is our object to provide 15 a support adapted to be secured to the back of a hair dresser's chair and a means for holding toilet articles and the like, capable of being detachably mounted on said support and easily and readily adjusted 20 from one position to another.

Our invention consists in certain details, in the construction, combination and arrangement of the various parts of the device, whereby the objects contemplated are 25 attained, as hereinafter more fully set forth, pointed out in our claim, and illustrated in the accompanying drawing, in which:

Figure 1 shows a rear elevation of a hair dresser's chair, equipped with an attachment 30 embodying our invention. Fig. 2 shows a perspective view of the shelf. Fig. 3 shows a vertical, transverse, sectional view through the shelf and the supporting means, taken on the line 3—3 of Fig. 2, and Fig. 4 shows 35 a similar view taken on the line 4—4 of Fig. 2.

In the accompanying drawing we have used the reference numeral 10 to indicate generally a hair dresser's chair, having the 40 back 11. Detachably secured to the rear surface of the back 11 by means of screws or the like, near each side thereof, is a bracket 12. Supported by the brackets 12 and extending across the back of the chair, spaced 45 apart therefrom, are two parallel rods 13, spaced from each other in the same vertical plane. Mounted on the rods 13 is a supporting member 14, comprising a vertically arranged plate having at its upper edge a

downwardly opening channel or groove 15 50 and having near its lower edge a forwardly opening channel or groove 16. Formed on the supporting member 14 is a rearwardly extending shelf 17, provided with compartments formed by means of upwardly extending 55 walls and partitions 18 and 20. The shelf 17 may support toilet preparations, containers 21, toilet articles 22 and the like.

We preferably form the bottom 19 of the portion of the shelf 17 of material having 60 openings in it to reduce the weight of the shelf. The bottom portion 19 also permits water to pass through, which is desirable in certain operations.

In the practical use of our improved attachment for hair dressers' chairs, a shelf may be attached and used on a table or when desired may be mounted on the rods 13 and used adjacent to the chair. It is desirable to have toilet articles and preparations as convenient of access as possible to the chair. It is also desirable that the container for such articles be adjustable to permit the hair dresser to be as close as possible to the customer. 75

It will readily be seen that the shelf of our attachment may be moved longitudinally on the rods 13 to any desired position. The shelf may be quickly and easily removed by swinging it upwardly on the upper rod and then elevating it until the channel 15 clears the upper rod 13. 80

It will be understood that some changes may be made in the details of the construction of our device, without departing from 85 its essential features, and it is our purpose to cover by this application any such changes which may be included within the scope of the following claim.

We claim as our invention: 90

In a device of the class described, the combination of a chair, with a pair of spaced alined brackets secured to the back thereof, parallel horizontal rods mounted in said brackets and a combined receptacle and 95 bracket comprising a horizontal plate having a vertical extension at one side, said extension being provided at its upper edges

with a portion curved forwardly and downwardly to form a downwardly opening channel, and with a laterally extending ridge near its lower edge and with a shorter downwardly and laterally extending ridge below the first ridge, the outer surface of said extension between said ridges being concave, said plate and extension being narrower than the distance between said brackets, so

that the plate can be readily slid along the 10 rods and also readily detached therefrom.

Des Moines, Iowa, February 21, 1914.

NETTIE REES.
GLADYS REES.
